UNITED STATES PATENT OFFICE.

MORLAND MICHOLL DESSAU, OF LONDON, ENGLAND.

PLAYING BALL, FLOAT, AND THE LIKE.

Application filed April 19, 1923. Serial No. 633,290.

To all whom it may concern:

Be it known that I, MORLAND MICHOLL DESSAU, a citizen of the United States of America, residing at London, England, have 5 invented Improvements in or Relating to Playing Balls, Floats, and the like, of which the following is a specification.

The present invention which relates to playing balls, floats and the like, has for 10 its object to increase their resiliency or flotation properties whilst maintaining the feature of solidity which prevents collapse through puncturing. To this end, in the 15 case of playing balls, for example in lieu of employing a core of spongy rubber as has heretofore been proposed encased within an outer covering of smooth and durable india rubber, the invention consists in 20 building up the core of strip material conveniently of the kind known commercially as plantation or crêpe rubber, and smoked sheets, the said strip material in the raw state being first twisted or otherwise acted 25 upon to impart a uniform or more or less irregular cord like character to it. The core which may be built up entirely of such material, by winding, or partially of such material wound upon a nucleus of rubber, 30 crumpled paper, fibre, metal, glass or other similar or suitable material may be subsequently subjected to a vulcanizing process, preferably a cold vulcanizing process such as that known as the Peachey process. In 35 this way a core is obtainable having interstices bounded by walls of a relatively crisp or springy nature which produces extreme resiliency and highly enhanced bouncing properties.

40 The ball may be completed by the provision of any of the usual coverings.

Alternatively the cords may be dressed with sulphur or vulcanizing ingredients and the whole or surface thereof may be vulcanized in the usual manner.

45 Or the materials of raw rubber used may be treated by first immersing in boiling alkaline solutions such as carbonate of soda, silicate of soda, potash or the like and cords 50 formed from the mass, by spewing through dies to any gauge.

The invention may be applied to tennis balls, golf balls, floats for valves and fishing purposes, life buoys, cushions, buffers of all descriptions, washers and so forth.

55 In the accompanying drawings, Fig. 1 is a view illustrating a portion of crêpe rubber strip partially twisted. Fig. 2 is a view of a ball with parts removed and partially in section in which strip according to Fig. 1 is incorporated. Fig. 3 is a view of a fishing float according to the invention. Fig. 4 shows forms of rubber cord hereinafter referred to.

60 As shown in Fig. 2, a nucleus *a* of crumpled paper has wound thereon the twisted strip material *b*, and having an outer cover *c* of ordinary smooth rubber.

65 The float in Fig. 3 comprises an outer covering *d* of smooth rubber the interior of which is filled with twisted rubber strip as referred to.

70 A nucleus of solid crêpe or smoked sheet rubber, or rubber disintegrated or devilled, may be formed and wound with the cord.

75 If preferred, a cord *e* may be formed with transverse strips *f* as shown in Fig. 4, so as to produce a multiplicity of air cells *g* when wound.

80 I am aware that it has been proposed to make balls for use in golf and the like games of twisted rubber bands or tapes which have been formed plain and flat, perforated to form a meshwork or netting or with surface corrugations, hollow cups or other projections or indentations as well as constituted of a number of threads or cords interlaced or tied by cross pieces, all of which expedients are directed to the formation of air cavities, and no claim is made to any such means, the present invention being directed to the employment of raw rubbers of commerce which have a naturally rough surface through the agency of which the air cavities are formed, these qualities being found in so called crêpe or plantation smoked sheet rubbers.

85 What I claim is:

90 1. In a device of the class described, in combination, a nucleus, strips of crêpe rubber twisted separately to form cords and

wound upon said nucleus to form a body having air cells which increase its buoyancy and a cover for said body.

2. In a device of the class described, in combination, a nucleus, strips of crêpe rubber twisted separately to form cords and wound upon said nucleus to form a body

having air cells which increase its buoyancy, said body having a vulcanized surface or cover integral therewith.

Signed at London, England, this 23rd day of March, 1923.

MORLAND MICHOLL DESSAU.
